LID SUPPORT

Albert F. Lickteig, Grand Rapids, Mich., assignor
to Grand Rapids Brass Company, Grand
Rapids, Mich., a corporation of Michigan

Application August 9, 1939, Serial No. 289,100

5 Claims. (Cl. 217—60)

The present invention relates to lid supports and more particularly to supports for horizontally hinged lids of cabinets or the like and which supports include means for counterbalancing the weight of the lids to insure smooth opening and closing of the lids and furnish support for the lids in partially open positions.

The primary objects of the instant invention are to provide an improved lid supporting device of the character above indicated, to provide such a device which may be readily adjusted after installation in a cabinet to counterbalance the weight of the cabinet's lid, to provide such a device which may be readily and conveniently installed in the cabinet, and to provide such a device which is attractive in appearance, effective in use and economical in manufacture.

An illustrative embodiment of the invention is shown in the accompanying drawings, wherein:

Figure 1 is an inside elevational view of the lid support installed on a cabinet, the cabinet and lid thereof being shown fragmentarily in vertical section;

Figure 2 is a sectional view thereof on line 2—2 of Figure 1;

Figure 3 is a sectional view through the lid supporting device on line 3—3 of Figure 2;

Figure 4 is a fragmentary inside elevational view of the device, an assembly screw thereof being omitted in this view;

Figure 5 is a perspective view of a pin element of the device;

Figure 6 is a perspective view of a spring washer element thereof;

Figure 7 is a central horizontal sectional view of the device partially disassembled and illustrating a method and means for adjusting the counterbalancing effect of the device;

Figure 8 is an inside elevational view of a modified form of the lid support;

Figure 9 is a sectional view thereof on line 9—9 of Figure 8;

Figure 10 is a sectional view thereof on line 10—10 of Figure 8; and

Figure 11 is a sectional view thereof on line 11—11 of Figure 10.

Referring to Figures 1-7 of these drawings wherein like parts are designated by the same numerals in the several views, a cabinet 10 having a side wall 11 and rear wall 12 is provided with a closure for the open top thereof here shown as a lid 13 mounted on the rear wall 12 by means of hinges 14.

A housing 15 is secured to the side wall 11 of the cabinet as by wood screws 16 passing there-

through, said housing comprising a casting having therein a recess 17, an elongated chamber 18 having a reduced annular portion 19, and a bearing 20 through the wall therof coaxial with the annular portion 19 of the chamber 18. A pin 21, shown per se in Figure 5, comprises a shank 22 having a longitudinal slot 23 therethrough, an enlarged annular circumferential flange 24 rotatably bearing in the reduced annular portion 19 of the chamber 18, a bearing portion 25 journaled in the bearing 20 of the housing and extending slightly beyond the bearing to form a shoulder 26, a reduced portion 27, and a peripherally serrated outer end portion 28.

A flat spiral spring 29 disposed in the chamber 18 of the housing 15 is provided with a turned-over inner end 30 fixedly seated in the slot 23 of the shank 22 of pin 21, the outer end 31 of the spiral spring 29 being fixedly hooked over a post 32 cast integrally with the housing 15.

A base plate 33 is snugly fitted in the recess 17 of the housing 15, and is secured therein by means of studs 34, 35 integrally cast on the housing and on the post 32 respectively, said studs extending through apertures in the base plate 33 and being swaged to securely join the housing and the base plate. This base plate is provided with a boss 36 which forms a bearing for the shank 22 of pin 21, a cap 37 being interposed between the shank 22 and boss 36. The side wall 11 of the cabinet is provided with a bore 38, drilled at the time of installation of the lid support, which bore accommodates the boss 36 of the base plate 33.

A radially undulated spring metal washer 39, shown per se in Figure 6, is interposed between the enlarged annular flange 24 of pin 21 and the bottom of the reduced annular portion 19 of the chamber 18 in the housing 15. This spring washer 39 urges the pin 21 toward the base plate 33 thus properly positioning the flat spiral spring 29 in the chamber 18 and restraining the pin 21 against longitudinal movement relative to the housing 15. Said spring washer 39 further serves as a stabilizing brake, exerting sufficient pressure on the parts to maintain the lid 13 in its set position above a predetermined angle.

An arm 40 is provided at one end thereof with an internally serrated opening 41 adapted to receive the peripherally serrated outer end portion 28 of the pin 21, the serrations of the pin 21 being adapted to engage the serrations of the arm 40 in various angularly turned positions of the arm relative to the pin, and when thus engaged these members, the pin 21 and arm 40, are

fixedly secured against relative rotating movement.

An assembly screw 42 has its shank 43 threaded in an internally threaded central opening 44 in the pin 21, the head 45 of said assembly screw 42 securely engaging the arm 40 therebetween and between the shoulder 26 on the pin 21 thus fixedly securing the arm 40 on the pin 21.

A link 46 is pivotally connected at 47 to the outer end of the arm 40 and is pivotally connected at 48 to a bracket 49 secured to the lid 13 of the cabinet in any suitable manner.

After installation of the lid supporting device on the cabinet, the tension on the flat spiral spring 29 may be very finely adjusted to counterbalance the weight of any lid, within prescribed limits, by removing the assembly screw 42 and sliding the arm 40 off the serrated end portion 28 of the pin 21, whereupon a suitable threaded wrench 50 (see Figure 7) may be passed through the opening 41 in the arm 40 and threaded into the internally threaded central opening 44 in the pin 21. By means of the wrench 50 thus inserted, the pin 21 may be manually turned to adjust the tension of the spiral spring 29 and when the required tension is achieved, arm 40 is replaced on the pin 21 and the tension is maintained by the engagement of the serrations on the arm with the serrations on the pin.

30 The assembly screw 42 is replaced after the flat spiral spring has been so adjusted as to counterbalance the weight of the lid so that the lid will remain in any open position or will fall smoothly and softly to closed position, as desired. Preferably the spiral spring is adjusted to maintain the lid in open position above a prescribed angular inclination of the lid, below which prescribed angular inclination the spiral spring is increasingly tensioned thus cushioning the closing movement of the lid under its own weight.

It will be seen that the housing 15 is symmetrical with respect to a horizontal center line, and that therefore identical parts may be installed on the opposite side wall of the cabinet 45 from the wall 11 shown in the drawing, by merely inverting the housing 15 and reversing the position of the spiral spring therein.

In the modified form of the invention illustrated in Figures 8-11, the arm 40¹ is freely rotatably mounted on a bearing portion 51 of the pin 21¹, but is coupled to the pin 21¹ by means of a disk 52 having an internally serrated central opening 53 engaging the peripherally serrated outer end portion 28¹ of the pin 21¹, said disk 52 having radial ratchet teeth 54 thereon engaging radial ratchet teeth 55 on the arm 40¹. A spring washer 56 interposed between the disk 52 and assembly screw 42¹ is compressible to permit relative movement in one direction between the disk 52 and arm 40¹, and said movement may be effected to increase the tension on the flat spiral spring 29¹ without removing the assembly screw 42¹ by manually engaging the teeth of a spanner wrench (not shown) into circumferential sockets 57 in the disk 52 and turning the wrench.

The invention may be further modified, and as likewise shown in Figures 8-11, by forming the housing of stamped metal parts comprising a main stamping 58 secured to the side wall 11¹ of the cabinet 10¹ as by screws 16¹ and a secondary stamping 59 having tongues 60 extending through slots 61 in the main stamping 58, these tongues being clinched to rigidly secure the stampings together. In this construction,

the pin 21¹ has a bearing 62 in the main stamping 58, a bearing 63 in the secondary stamping 59, and a bearing 64 in the base plate 33¹, and the spring metal washer 39¹ is here interposed between the main stamping 58 and a washer 65 abutting the circumferential flange 24¹ on the pin 21¹.

In Figures 8, 10 and 11 is shown a stop for limiting the upward movement of the hinged lid 13¹ of the cabinet, said stop comprising a stud 66 on arm 40¹ adapted to abut a projection 67 on the main stamping 58 to stop the arm 40¹ at a predetermined elevated position.

While but several specific embodiments of the invention have been herein shown and described, it will be understood that certain details of the constructions shown may be altered or omitted without departing from the spirit of this invention as the same is defined by the following claims.

I claim:

1. A counterbalancing device for a horizontally hinged lid of a cabinet or the like comprising a housing mounted on the cabinet and having a chamber therein and a horizontal bearing through the wall thereof, a base plate secured to the housing and having a horizontal bearing therein in alignment with the bearing in said housing, a pin rotatably disposed in said bearings and projecting outwardly beyond the housing, a spiral spring disposed in the chamber and having its inner end fixedly secured to the pin and having its outer end fixedly secured to the housing, an arm mounted on the outer end of the pin and turnable with the pin, and a link pivotally secured at one end thereof to the outer end of the arm and pivotally secured at the other end thereof to said lid.

2. A counterbalancing device for a horizontally hinged lid of a cabinet or the like comprising a housing mounted on the cabinet and having a chamber therein and a horizontal bearing through the wall thereof, a base plate secured to the housing and having a horizontal bearing therein in alignment with the bearing in said housing, a pin rotatably disposed in said bearings and projecting outwardly beyond the housing, said pin having a circumferential flange, a spring interposed between said flange and the housing, a spiral spring disposed in the chamber and having its inner end fixedly secured to the pin and having its outer end fixedly secured to the housing, an arm mounted on the outer end of the pin and turnable with the pin, and a link pivotally secured at one end thereof to the outer end of the arm and pivotally secured at the other end thereof to said lid.

3. A counterbalancing device for a horizontally hinged lid of a cabinet or the like comprising a housing mounted on the cabinet and having a chamber therein and a horizontal bearing through the wall thereof, a base plate secured to the housing and having a horizontal bearing in alignment with the bearing in said housing, a pin rotatably disposed in said bearings and having a peripherally serrated portion projecting outwardly beyond the housing, a spiral spring disposed within the chamber and having its inner end fixedly secured to the pin and having its outer end fixedly secured to the housing, an arm having an internally serrated opening therein adapted to engage the peripherally serrated outer end portion of said pin in selected turned positions of the arm relative to the pin, and a link pivotally secured at one end

thereof to the outer end of the arm and pivotally secured at the other end thereof to said lid.

4. A counterbalancing device for a horizontally hinged lid of a cabinet or the like comprising a housing mounted on the cabinet and having a chamber therein and a horizontal bearing through the wall thereof, a base plate secured to the housing and having a horizontal bearing in alignment with the bearing in said housing, a pin rotatably disposed in said bearings and having a peripherally serrated portion projecting outwardly beyond the housing, a spiral spring disposed within the chamber and having its inner end fixedly secured to the pin and having its outer end fixedly secured to the housing, an arm having an internally serrated opening therein adapted to engage the peripherally serrated outer end portion of said pin in selected turned positions of the arm relative to

the pin, an assembly screw removably threaded in said pin for securing the arm against movement relative to the pin, and a link pivotally secured at one end thereof to the outer end of the arm and pivotally secured at the other end thereof to said lid. 5

5. A counterbalancing device for a horizontally hinged lid of a cabinet or the like which has a bore in its side, said device comprising a housing mounted on said side and having a base plate with a boss extending into said bore and forming a bearing for the hereinafter mentioned pin, a pin mounted in the housing turnable in the bearing formed by said boss, a spiral spring within the housing having its inner end secured to the pin and its outer end secured to the housing, an arm mounted on the pin turnably therewith, and a link pivotally connected with the outer end of the arm and with the lid. 10 15
